US0D1013642S

(12) **United States Design Patent** (10) **Patent No.:** **US D1,013,642 S**
(45) **Date of Patent:** **** Feb. 6, 2024**

(54) **CONNECTOR**

(71) Applicant: **J.S.T. Corporation**, Farmington Hills, MI (US)

(72) Inventors: **Eric Blankinship**, Lathrup Village, MI (US); **Ping Chen**, Novi, MI (US); **Kurt Hutchison**, Novi, MI (US); **Gwendolyn Upson**, Ypsilanti, MI (US)

(73) Assignee: **J.S.T. Corporation**, Farmington Hills, MI (US)

(**) Term: **15 Years**

(21) Appl. No.: **29/881,686**

(22) Filed: **Jan. 5, 2023**

Related U.S. Application Data

(63) Continuation of application No. 29/766,014, filed on Jan. 13, 2021, now Pat. No. Des. 975,025.

(57) **CLAIM**

The ornamental design for a connector, as shown and described.

DESCRIPTION

FIG. 1 is a top front perspective view of a connector showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top front perspective view of another connector showing the claimed design;

FIG. 10 is a bottom rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The dashed broken lines in the figures show portions of the connector that form no part of the claimed design.

The dot-dash broken lines in the figures show boundaries that form no part of the claimed design.

1 Claim, 12 Drawing Sheets
